CHAIR

Caryl F. Williams, La Canada, Calif., assignor to Brown-Jordan Co., Pasadena, Calif., a partnership composed of Robert E. Brown and Hubert W. Jordan

Application May 7, 1948, Serial No. 146,216

Term of patent 14 years

(Cl. D15—1)

To all whom it may concern:

Be it known that I, Caryl F. Williams, a citizen of the United States, residing at La Canada, in the county of Los Angeles and State of California, have invented a new, original, and ornamental Design for a Chair, of which the following is a specification, reference being had to the accompanying drawing, forming a part thereof, in which:

Fig. 1 is a front perspective view of a chair, showing my new design;

Fig. 2 is a side perspective view thereof; and

Fig. 3 is a rear perspective view showing my new design.

I claim:

The ornamental design for a chair, substantially as shown.

CARYL F. WILLIAMS.
